FIG. 3

FIG. 1

FIG. 2

FIG. 4

FIGURE 1 is a side elevational view of the liquid-vapor valve showing the new design.

FIGURE 2 is a front elevational view of the liquid-vapor valve.

FIGURE 3 is a plan view of the liquid-vapor valve.

FIGURE 4 is a side elevational view opposite FIGURE 1 of the liquid-vapor valve shown in reduced scale.

The dominant features of the design reside in the portions shown in full lines.

The stem, shown in broken lines, is broken away to indicate indeterminate length.

We claim:

The ornamental design for a liquid-vapor valve, substantially as shown and described.
